UNITED STATES PATENT OFFICE

2,682,228

LIQUID FUEL PUMP FOR INTERNAL-
COMBUSTION ENGINESJan Van Buuren, Amsterdam, Netherlands, as-
signor to Werkspoor N. V., Amsterdam, Nether-
lands, a company of the Netherlands

Application February 15, 1949, Serial No. 76,625

Claims priority, application Netherlands
February 17, 1948

1 Claim. (Cl. 103—47)

1

The invention relates to a fuel pump for an internal combustion engine of the injection type, said pump being driven by a driving member which is moved mechanically in correlation with the piston in the motor cylinder served by the fuel pump, the fuel injector being of the type which opens mechanically when a predetermined, generally adjustable fuel pressure is attained.

In engines of the kind referred to of normal design having direct injection, the pump is usually driven by a cam fixed on a camshaft, driven by the crankshaft. The connection of this pump to its driving devices is constituted by a positive drive, so that the movement of the pump shows a predetermined relation with the movement of the piston. This construction gives a certain rigidity to the system, resulting i. a. in the necessity of using in general different driving devices (two different cams) for the forward and backward rotation of the engine for fore and aft movement, because, as a matter of fact, the movement of the fuel pump has to show a certain phase shift with respect to the dead-centre of the power piston movement at the end of the compression stroke of the engine (preinjection).

The invention is based on the principle that this rigidity can be avoided by introducing a certain independence of movement between the fuel pump and the member by which the latter is driven, it being realized, however, that power transmission between these devices remains constantly required during the power stroke of the pump.

Then the movement of the pump is no longer controlled by the course of the movement of the driving members, but the pump is able to function all the time that the force exerted by the driving devices is great enough and has also the right direction to bring about that operation.

In accordance with the invention the driving device, which has a reciprocating motion, moves for that purpose the active piston of a pneumatic transmission system, the passive piston of which is connected to the fuel pump.

So in that case the rigid connection between driving device and fuel pump is replaced by an energy accumulator, which may be easily given a great power and which is easily adjustable.

The term "pneumatic system" implies any system in which gaseous fluids are used.

According to the invention the active member will get in general a harmonic movement, which is mostly derived from a driving rod and crank movement. This feature becomes especially evident when the active device is moved in phase

5 (by which in this connection may be occasionally understood "in counter phase" too) with the motor piston. This case occurs when the active member is driven from a pump (scavenging piston pump, supercharging piston pump) driven by the power piston, so that no camshaft is required. Then the power piston and the mentioned active member simultaneously pass the dead-centre. At this movement the speed of the active member decreases in the second half of the power stroke, and during that time the energy accumulator must supply energy to enable the passive member to push fuel at least with non-decreasing force and speed and to effect the fuel injection about 15 the moment when the power piston passes the dead-centre, in the right manner and at the right moment.

In order that the mentioned supply of energy may take place, according to the invention the 20 passive member may be connected to the fuel pump by means of a mechanism, which causes the ratio of the driving forces supplied and absorbed by it to vary dependent on the movement, i. e. in such a manner that this ratio is maintained as it is or is increased towards the end of 25 the active pump stroke. The mechanism referred to is preferably a crank mechanism with two (shifted) cranks enclosing an angle between them.

It may be pointed out that it is already known 30 to drive a fuel pump as referred to above by means of a passive piston moved by a gaseous fluid under pressure (Archaoulff system). With this system, the gaseous fluid is derived from the 35 gaseous contents of the power cylinder (motor cylinder), no independent active piston being present. Moreover, the independent gaseous mass which, according to the invention, functions as an energy accumulator, creates a better adjustability than the dependent gaseous mass 40 which is used in the known system. For in the last mentioned system the compression pressure, e. g. when the engine is started, may be so low that no injection takes place.

45 The drawing illustrates an embodiment of the invention.

Fig. 1 is a somewhat diagrammatic vertical cross section of a two-stroke internal combustion engine with longitudinal flow scavenging, provided with a fuel pump system according to the 50 invention.

Fig. 2 diagrammatically illustrates the fuel pump system in a different position, on a larger scale and more complete.

Fig. 3 represents a cross section of a constructional form of the system according to Fig. 2.

In Fig. 1, 1 is the power or motor cylinder provided with a separate cylinder liner 2. The cylinder is closed by the cylinder head 3 shown in front elevation; the cylinder head contains a central fuel injector 4 and exhaust valves 5 grouped around the injector 4. The exhaust outlets communicate with the exhaust pipe 6.

The cylinder liner 2 contains the scavenging and/or supercharging ports 7, which terminate in the air chamber 8; 9 is the piston with piston rod 10.

Adjacent the power cylinder is the scavenging pump cylinder 11 with the piston 12. Its plunger rod 13 is driven from the lever 14 pivoted on the fixed point 15 and driven by the coupling rod 16, which is pivoted at 17 on the piston 9.

The piston rod 13 of the scavenging pump is extended through the upper cylinder cover 18 of the scavenging pump and bears there a piston 19. This piston moves in a cylinder 20, which cylinder communicates at its top with a cylinder 21, in which a piston 22 moves. Via piston rod 23 and coupling rod 24 this piston 22 engages the end of the lever 25, which can rock around the fixed pivot 26. This lever 25 is provided with an arm 27, which has a fixed angular position with respect to the lever 25. So the lever 25 with arm 27 forms a crank mechanism with two cranks which are placed at an angle, i. e. which are shifted.

The end of arm 27 is provided with a driving rod 28, connected to a crosshead 29, from which crosshead 29 a plunger 30 of the fuel pump 31 is driven. The crosshead 29 is controlled by a pressure spring 32, which biases the crosshead downwardly. The lever 25 which is pivoted about the fixed pivot 26 and has pivotal connections with the links 24 and 28 may be considered as being a bell crank lever.

When the power piston ascends, i. e. makes the compression stroke, the scavenging pump driving rod 13 is also ascending and the piston 19 too. The air above this piston 19 in the cylinder 20 is compressed; this air also enters the cylinder 21 and there drives the piston 22 upward, which movement is converted into a pump stroke of the fuel plunger 30. The fuel which has been drawn in through the pipe 34 is pressed away through the pressure valve 35 and the pipe 36 to the injector 4, which opens when a certain pressure is attained, so that the fuel is allowed to enter the power cylinder 1.

It stands to reason that the speed of the active piston 19 decreases towards the top dead-centre and changes its direction after having passed the dead-centre. The crank mechanism 25, 27 operates in such a manner that the force exerted on the fuel plunger 30 nevertheless goes on increasing or at least remains the same, which is necessary to continue the fuel injection process. The cause of this phenomenon is that the force P (see Fig. 2), which is exerted by the driving rod 28 on the fuel plunger 30, is imparted to it by the lever arm B which becomes smaller with respect to the fixed pivot 26, whereas the force P₁ which is exerted by the passive piston 22, is applied to the couple arm C which changes only slightly.

Now it is deduced from the momentum equation that

$$P = P_1 \times \frac{C}{B}$$

Owing to the decrease of B, P increases towards the end of the stroke notwithstanding the decreasing of P₁.

When the active piston 19 descends further, after the injection, the passive piston 22 follows this descent, also under the influence of the spring 32, which controls the crosshead 29. When the active piston 19 is in its lowest position, it opens the ports 38 in the wall of the cylinder 20, so that the pneumatic system can be refilled with air. Occasionally these ports 38 can communicate with the scavenging air system or the pressure charging system. When the load of the engine is increased, the pressure of the scavenging air or of the supercharging air increases with the result that the pressure level in the pneumatic system of the fuel pump increases and that consequently the injection during higher loads takes place earlier.

Between the active piston and cylinder 19, 20 and the passive piston and cylinder 21, 22 a valve mechanism 40 is inserted. In the situation according to Fig. 1 the space in the cylinder 21 above the passive piston 22 according to the arrow 41 is in free communication with the open air. So the passive piston 22 can ascend freely to the end of its stroke. The function of the valve mechanism 40 is to make it possible to restrict this free movement in order to create an adjusting facility for the fuel injection.

When the valve mechanism 40 is moved downward, the upper head 42 closes the outlet 41 to the open air. The head 43 opens the overflow way 44, so that the spaces above and below the passive piston 22 and the space above the active piston 19 are going to communicate (Fig. 2). Owing to this operation the movement of the passive piston 22 is stopped.

The only function of the valve head 45 is to keep the system closed.

The valve mechanism 40 is connected to a lever 46, pivoted on the temporarily fixed point 47. The lever 46 is connected at its end by the rod 48 to an end of the lever 25 situated beyond the fixed pivot 26. So when the passive piston 22 is approaching its upper terminal position, the lever 46 automatically brings the valve mechanism 40 in the position according to Fig. 2, during which overflow takes place and the movement of the passive piston 22 is stopped. Now adjustability is obtained by making the temporarily fixed pivot 47 shiftable, which can be realized by placing it on a crank pivoted on the point 50.

In the system of rods a lever 52 has, moreover, been inserted pivoting on the fixed point 53, which lever is connected by means of a coupling rod 54 to the lever 25. The lever 52 can co-operate with a collar 55 on the piston rod 13. This co-operation is to take place just before the highest position of the active piston, so that an initial movement in the direction of the pump will be given to the system.

Fig. 3 sectionally shows the constructional form of the system of active and passive piston. The same references have been used as in Figs. 1 and 2, so that further elucidation is superfluous. The crank 60 pivoted on 50 takes the zero position in the position 61 and the full load position in the shown position 62.

What I claim is:

In a liquid fuel injection pump device, a pump plunger and a driving mechanism therefor, said driving mechanism comprising, in combination, a cylinder having a piston therein responsive to fluid pressure, a lever system for transmitting

movement of the piston to the pump plunger including a bell-crank mounted on a fixed pivot between the cylinder and the pump plunger, a first link pivotally connecting one arm of the bell-crank to the piston and a second link pivotally connecting the other arm of the bell-crank to the pump plunger, the bell-crank being so related to the pivotal connections with the links as to move the pump plunger with undiminished force as the piston approaches the end of the power stroke, and means operatively connected to the bell-crank for imparting an initial movement thereto in the power stroke of the pump plunger just prior to such movement being effected by the power stroke of the piston.
